UNITED STATES PATENT OFFICE.

ERNST EDUARD MARTIENSSEN, OF HAMBURG, GERMANY.

DRAINAGE SYSTEM FOR PLAYING GROUNDS.

Application filed April 12, 1927, Serial No. 183,220, and in Germany December 29, 1925.

This invention relates to a system conditioning the surface of playing grounds, tennis courts and the like having a drainage or foundation layer.

5 Tennis courts as heretofore constructed suffer from the drawback that the upper layer dries up very quickly and is then too dusty. A consequent additional drawback is rapid wear of the surface, so that frequent 10 repairs of the upper layer are necessary, involving considerable expense. To prevent the formation or the rising of dust, it was common practice to moisten the ground by sprinkling, but even this involves labour 15 and cost.

These drawbacks result from the endeavour to lead away the rain water as quickly as possible, so as to keep the upper layer or surface free from water. The leading off of the rain water is either effected by 20 inclining the court and conducting the water from the upper surface into a drain, or by giving the water an opportunity to infiltrate to a greater depth; also both expedients have been adopted concomitantly. It 25 is true that even after heavy rain quick drying up of the ground has been insured, but the drying is found to be so rapid and complete that formation of dust on the upper 30 layer is an inevitable consequence.

The object of the present invention is to secure a permanently correct condition of playing grounds or courts and above all to prevent full drying up of the covering or 35 surface layer, which is liable to cause the development of dust.

With this object, according to the invention, the intermediate carrying or foundation layer between the covering layer and the natural or artificial impermeable layer 40 is so constructed or so conditioned that it is adapted to take up a certain amount of water and to hold it for a considerable time. This draining foundation layer, owing to its contents of water, automatically 45 gives up moisture to the covering layer at such a rate that the latter cannot dry up to such an extent as to occasion the development of loose dust.

50 In order to promote the transmission of moisture to the covering layer and in order to regulate the amount of moisture within the layer in case continued drought or frequent heavy rains should influence the condition of the playing ground there is provided a sluice valve or other regulator for

controlling the water running off the carrying layer. This valve serves as a means of controlling the moistness of the playing ground and therefore the prevailing conditions. The water which heretofore was allowed to run off uselessly can now be utilized during dry weather, while the playing ground can be kept in such a condition that it may be used in continued wet weather by 60 fully opening the valve.

In the accompanying drawing Figs. 1 and 2 illustrate two embodiments of the invention.

In both constructions shown the playing 70 ground consists of the covering layer *a* made of any material known heretofore in usual manner, the impermeable layer *b* and the foundation layer *c* disposed between the two first named layers. The impermeable layer 75 *b* may be natural if the soil consists of clay. The foundation layer *c* may be composed of broken up bricks, the intermediate spaces or interstices being filled up with brick powder or even better with kieselguhr, or 80 ashes either in a dry state or by the aid of water. The broken-up bricks form the carrying means, while the brick powder or kieselguhr on account of its water-absorbing capacity serves for taking up and giving off 85 the moisture to the covering layer *a*.

In the construction shown in Fig. 1 the foundation layer is provided with a plurality of drain pipes *e* having a certain amount of slope and connected with one another, one of them leading into a vertical drain pipe *f*. In front of the outlet is provided a sluice valve *g*, as the case may be, which prevents or limits or allows the running off of water taken up by the drain 90 pipes *e*.

The tennis court shown in Fig. 2 has an inclined impermeable layer *b*. The inclination is greatest near the edge, and at this place is arranged the vertical drain pipe *f* having 100 a branch *h* open to the foundation layer *c*. The valve *g* is arranged in this branch pipe.

In both cases by the aid of the valve *g* the amount of moisture or water within the foundation layer *c* may be regulated at will. 105

I claim:—

1. A conditioning system for hard tennis courts comprising a lowermost impermeable layer, the playing surface, and an intermediate layer in contact with said surface and said impermeable layer, said intermediate layer being constructed of such material as 110

to take up and retain water draining through the surface layer, and automatically to maintain a rate of moisture exchange with the surface layer when the latter becomes drier than the adjacent part of the intermediate layer, and means varying the level of water in said intermediate layer for varying the rate of moisture exchange.

2. A conditioning system for hard tennis courts comprising a lowermost impermeable layer, the playing surface, and an intermediate layer in contact with said surface and said impermeable layer, said intermediate layer being constructed of such material as

to take up and retain water drained through the surface layer, and automatically to maintain a rate of moisture exchange with the surface layer when the latter becomes drier than the adjacent part of the intermediate layer, and means varying the level of water in said intermediate layer for varying the rate of moisture exchange, said means comprising a drain pipe and suitable valve arranged near the lower regions of said intermediate layer.

In testimony whereof I have signed my name to this specification.

ERNST EDUARD MARTIENSSEN.
